Specification for Design.

Patented May 20, 1913.

Application filed October 28, 1912. Serial No. 728,298. Term of patent 7 years.

To all whom it may concern:

Be it known that I, JULIA SWARTZENBURG, a citizen of the United States, residing at Omaha, in the county of Douglas and State of Nebraska, have invented a new, original, and ornamental Design for a Thermostat, of which the following is a specification, reference being had to the accompanying drawing, forming a part thereof.

Figure 1 is a side view of a thermostat, showing my new design. Fig. 2 is a plan

view of the thermostat. Fig. 3 is an end view of the same.

I claim:

The ornamental design for a thermostat, as shown.

In testimony whereof I have affixed my signature in presence of two witnesses.

JULIA SWARTZENBURG.
